CLAIM

The ornamental design for a decorative molding, as shown and described.

DESCRIPTION

FIG. 1 is a top plan view of a decorative molding showing my new design shown broken away to indicate indeterminate length with the pattern being continuous throughout its length;

FIG. 2 is a bottom plan view thereof;

FIG. 3 is a left side elevational view thereof;

FIG. 4 is a right side elevational view thereof;

FIG. 5 is a front elevational view thereof, the back being a mirror image thereof; and,

FIG. 6 is a fragmentary, top, front, left side perspective view thereof.
